(57) **CLAIM**

The ornamental design for a head holder pad, as shown and described.

DESCRIPTION

FIG. 1 is a front-bottom-left perspective view of a head holder pad according to the present invention.

FIG. 2 is a front-top-right perspective view of the head holder pad.

FIG. 3 is a bottom view of the head holder pad.

FIG. 4 is a top view of the head holder pad.

FIG. 5 is a right side view of the head holder pad.

FIG. 6 is a left side view of the head holder pad.

FIG. 7 is a front view of the head holder pad.

FIG. 8 is a rear view of the head holder pad.

FIG. 9 is a cross-sectional view taken along line 9-9 in FIG. 5.

FIG. 10 is a cross-sectional view taken along line 10-10 in FIG. 6; and,

FIG. 11 is a cross-sectional view taken along line 11-11 in FIG. 3.

The dash-dash broken lines in FIGS. 1-11 illustrate portions of the head holder pad that form no part of the claimed design.

1 Claim, 11 Drawing Sheets
